APPARATUS FOR TREATING STRIP STEEL

Aaron Simon, Brooklyn, N. Y., assignor to Triangle Mechanical Laboratories Corp., New York, N. Y., a corporation of New York

Application June 18, 1937, Serial No. 148,874

1 Claim. (Cl. 266—3)

This invention relates generally to a means for treating strip steel.

One of the objects of this invention is to provide an apparatus for treating strip steel of the type, for example, suitable for use in making razor blades and the like, in which the strip steel is heat treated so as to produce thereon a thin finish coating in the nature of a blue oxide film, the construction of the apparatus being such that the strip steel will be prevented from scaling, thus insuring uniformity and evenness of the blue finish.

Another object of this invention is to provide in combination with an apparatus of the character described for heat treating strip steel, an improved construction of chill means.

Still another object of this invention is to provide an apparatus of the character described for treating strip steel, which shall comprise relatively few and simple parts, which shall be inexpensive to operate, which shall be easy to assemble and maintain, and which at the same time shall operate with a high degree of efficiency.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claim.

In the accompanying drawings, in which is shown one of the various possible embodiments of this invention,

Fig. 1 is a diagrammatic view illustrating the continuous process of treating strip steel embodying this invention;

Fig. 2 is an enlarged horizontal section of a portion of the apparatus illustrated in Fig. 1;

Fig. 3 is an enlarged vertical section of a portion of the apparatus illustrated in Fig. 1;

Fig. 4 is an enlarged cross-sectional view taken substantially on the line 4—4 of Fig. 3;

Fig. 5 is an enlarged cross-sectional view taken substantially on the line 5—5 of Fig. 3;

Fig. 6 is an enlarged cross-sectional view taken substantially on the line 6—6 of Fig. 3;

Fig. 7 is a cross-sectional view taken substantially on the line 7—7 of Fig. 3; and

Fig. 8 is an enlarged cross-sectional view taken substantially on the line 8—8 of Fig. 7.

Referring now in detail to the drawings, there will be described an improved process and apparatus for treating strip steel of the type suitable for use as razor blades, but it is understood that

this invention may be satisfactorily practiced in connection with the treatment of steel suitable for other uses.

Referring particularly to Fig. 1 of the drawings, there is disclosed a diagrammatic arrangement of an apparatus for treating a supply of strip steel to produce a blue coating thereon. The supply of strip steel 10, from a roll R, supported on a stand 11, is fed through a muffle 12, passing through a furnace 14, where it is heated to a temperature above the lower critical point and then quickly quenched by means of a pair of chill blocks 15, to harden the same. It is then led through a pair of tension rollers 16 and through a tempering furnace 17, again cooled and led on through a second pair of tension rollers 18 to be wound up on a reel 19. The said reel 19 may be driven by any suitable driving mechanism, such as a motor 20.

The type of furnace 14 employed may be of the electrical type, as shown in Figs. 2 and 3, and comprising a top wall 21, a bottom wall 22, side walls 23, and end walls 24 and 25. Centrally disposed of the furnace is a longitudinal opening 25 in which there is positioned a muffle 12, said muffle being of suitable material and preferably made in the form of a flattened seamless tube open at both ends, as shown in Fig. 4. Surrounding a portion of the muffle 12 within the furnace 14 is a heating coil 30 preferably of one piece of suitable material and arranged in a series of convolutions spaced from and adapted to encase the top, bottom and one side of the muffle 12, as shown in Fig. 5. The spaces within the furnace between the opening 25 and the top and bottom walls 21 and 22 are filled with suitable heat insulating material such as fire brick. It is noted that the ends 12a and 12b of the muffle 12 project outwardly beyond the end walls 24 and 25 for a predetermined distance.

The heating coil 30 may be connected to any source of electrical supply by suitable conductor means (not shown). As the strip steel 10 is led through the muffle 12, it is heated to a temperature below the critical temperature in an atmosphere of such character that a thin uniform blue oxide coating is formed on the surface of the steel strip. This atmosphere may be provided by introducing into the muffle 12, together with the strip steel as it is fed through the furnace, a controlled supply of steam in such quantity that, together with the air inside the muffle 12, an oxidizing atmosphere is produced which, under said temperature, produces upon the steel a sub-oxide of iron, probably the ferrous oxide. The steam

40

50

55

may be introduced into the muffle 12 from a source of supply, such as a tank 31, through a hose connection 32 connected at the free end thereof to a specially designed nozzle member 33, having the open end thereof projecting inside of the muffle 12 for a predetermined distance.

The member 33 may comprise a flattened metallic tube made of a suitable material, such as brass and having a portion adjacent the end 33a thereof, which projects inside the muffle, pinched, as shown in Fig. 4, to distribute the flow of steam as it enters the muffle, and at the same time, to increase the pressure thereof. The member 33 is provided with a drain or outlet pipe 34 designed 15 to drain off the condensation or excess steam in the member 33. The member 33 may be slidably supported on a bracket 35 which is fixed to the wall 24 of the furnace 14 and which may be 20 slidably moved by means of a clamp 36 to adjust the distance which the end 33a projects inside the muffle 12.

It is well known that when steel heated to temperatures as high as the lower critical temperature thereof is exposed to the atmosphere, there 25 immediately forms upon the steel a flaky, non-adherent oxide coating, commonly called "scale". To preserve the thin, uniform blue finish imparted to the steel in the muffle 12, it is, therefore, essential to immediately quench the steel without 30 exposing any portion of it to the surrounding atmosphere upon its exit from the muffle. To this end, I have provided a novel construction of quenching or chill blocks which are so designed and arranged that the strip steel 10, upon leaving the furnace 14, will be quenched before coming in contact with the surrounding atmosphere. This novel construction will now be described.

It is noted that the end 12b of the muffle 12 extends beyond the wall 25 of the furnace 14 for a slight distance. A pair of chill blocks 37 and 38 are supported on a bracket 39 which is fixed to the wall 25 of the furnace 14. The chill blocks 37 and 38 are symmetrical in construction and comprise head portions 37a and 38a and integral shank 45 portions 37b and 38b. Each of the blocks 37 and 38 is of hollow construction and is provided with an inlet 40 and an outlet 41 adapted to supply to the interior of the blocks 37 and 38 a continuously flowing stream of cooling fluid, such as water 50 from a source of supply (not shown). The bottom surface 37c of the block 37 and the top surface 38c of the block 38 are adapted to be disposed in contacting relationship and each of said surfaces is provided with a centrally disposed 55 slightly recessed portion 42. The combined recesses 42 are adapted to be in registry when the blocks 37 and 38 are placed in superimposed relationship, as shown in the drawings, and to form a guideway for the passage of the strip of steel 10, 60 which is adapted to pass therethrough upon leaving the furnace 14. In order to prevent the surrounding atmosphere from scaling or otherwise affecting the strip of steel 10 as it leaves the muffle 12 to enter the recessed guideway 42 between the 65 chilling blocks 37 and 38, the head portions 37a and 38a of the chill blocks 37 and 38 are each provided with symmetrical recessed areas 44 and 45, which are designed so as to be of the same shape and contour as the outer surface of the muffle 12. The end 12b of said muffle is adapted 70 to be received in said recesses 44 and 45, as clearly shown in Figs. 3 and 7 of the drawings. The

recesses 44 and 45 are of predetermined depth so that the outer surfaces of the head portions 37a and 38a of the chill blocks will lie flush up against the wall 25 of the furnace 14 to form a substantially air tight seal surrounding the muffle 12.

It is thus seen from the above-described construction that when the strip 10 leaves the muffle 12, it will immediately enter the recess 42 between the chill blocks to be immediately quenched and hardened before the surrounding atmosphere has been able to act upon said strip to damage the same. As the strip 10 passes through the chill blocks to be cooled, it may then be led between the rollers 16 and into the tempering furnace 17, as previously described.

It is desirable that the recess 42 between the chill blocks be relatively slight so that no air will enter between the blocks to affect the blue coating thereon during the quenching or chilling process. The bottom walls 37c and 38c of the chill blocks 37 and 38 have, therefore, been constructed so as to be slidably removed after the recess 42 has been worn away by the friction of the passing of the strip 10 therethrough, in order to replace the walls 37c and 38c with new walls 25 containing the proper amount of recess. The walls 37c and 38c may be removably attached to the blocks 37 and 38 by any suitable attaching means, such as screws 45.

The furnace 14 may be provided with a thermostatic heat control device 50 to provide for automatically shutting off of the electric current when the temperature in the space 25 surrounding the muffle 12 has risen to a predetermined degree and to turn on the electric current whenever the temperature within the space 25 falls below a predetermined amount.

While in the operation of the above-described process and apparatus for treating strip steel a mixture of steam and air was introduced into the muffle to produce a blue oxide coating on the strip, it is understood that in the apparatus constructed in accordance with this invention there may be used other suitable atmospheres, such for example as a proper mixture of illuminating gas and air.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

In an apparatus for treating a strip steel of the character described, a muffle adapted to have a steel strip led therethrough to be heated to a predetermined degree of temperature, said muffle having an open end portion projecting outside of said furnace, a source of steam supply, and means for introducing steam from said source of supply into said muffle at said projecting open end, said last named means comprising a flattened tubular nozzle received within said muffle and having a drain outlet disposed outside of said muffle.

AARON SIMON,
